UNITED STATES PATENT OFFICE.

HENRY F. SCHWARTZ, OF PHILADELPHIA, PENNSYLVANIA.

REVOLUBLE SIGN AND REFLECTOR THEREFOR.

SPECIFICATION forming part of Letters Patent No. 563,808, dated July 14, 1896.

Application filed April 7, 1896. Serial No. 586,489. (No model.)

To all whom it may concern:

Be it known that I, HENRY F. SCHWARTZ, a citizen of the United States, residing at the city of Philadelphia, in the county of Philadelphia and State of Pennsylvania, have invented certain new and useful Improvements in Revoluble Signs and Reflectors Therefor, of which the following is a specification.

My invention has relation to a revoluble sign for use on street-cars to designate the route and provided with a reflector whereby either face of the sign may, when exposed at night, be illuminated, and in such connection it relates particularly to the construction and arrangement of such a sign and its reflector.

The principal objects of my invention are, first, to provide a revoluble sign for street-cars which may be simply and easily constructed and operated, said sign having a reflecting hood whereby either face may be illuminated when exposed at night; second, to provide in such a sign a frame secured to the car, the sign being removable from said frame, a key adapted to revolve the sign in the frame, miter-gears adapted to revolve said key, and a hand-wheel or lever adapted to revolve the gears; third, to provide in such a sign having the frame, the sign revoluble in the same, and the key adapted to revolve the sign, of a shaft operating miter-gears to revolve the key, said shaft being provided with two flat faces revolving between two leaf-springs and adapted to hold in required position the shaft, so that the sign may be turned to required position, and, fourth, to provide in such a sign a reflecting-hood removably secured to the frame above the sign.

My invention consists of a revoluble sign and reflector for street-cars constructed and arranged in substantially the manner hereinafter described and claimed.

The nature and scope of my invention will be more fully understood from the following description, taken in connection with the accompanying drawings, forming part hereof, and in which—

Figure 1 is a front elevation of the sign and reflector embodying features of my invention and illustrating the arrangement and construction of the same when in position upon the roof of the car. Fig. 2 is an en-

larged front elevation of the sign and reflector detached from the car, a portion of the hood being broken away to more clearly illustrate the construction and arrangement of the reflector. Fig. 3 is a top or plan view, enlarged, of the reflector, illustrating its connection with the roof of the car. Fig. 4 is a vertical section, enlarged, of the reflector, the sign, and a portion of the roof of the car. Fig. 5 is a longitudinal section, enlarged, illustrating in detail the key, its connection with the sign, and the miter-gear secured to the end of the key. Fig. 6 is a horizontal section, enlarged, illustrating in detail the flattened shaft, the hand-wheel adapted to operate the same, and the springs adapted to hold the shaft in required position; and Fig. 7 is a side elevation, enlarged, of the end support for the sign in the frame, illustrating locking means for securing the sign in the support.

Referring to the drawings, A represents the front or rear end of the roof of a car, to which is secured by means of brackets *a* a bent iron rod *b*, the ends of which pass through the brackets *a*, and are secured therein by means of nuts *b'*. Upon this rod *b* is suspended an open frame *d*, of rectangular outline, within which frame a sign-board *e* is adapted to revolve. The sign-board *e* is provided at one end with a pin *e'*, adapted to enter the recessed support *f* formed in the frame. The construction of this support *f* is illustrated particularly in Fig. 7, and the support is provided with a locking-arm *f'*, pivoted to the support above the recess *f* therein and adapted to be secured down upon the upper end of said recess by a spring-catch *f* fitting under the lower edge of the support *f*. This, while the preferred form, may be modified by making the arm *f'* and catch *f* in one piece without departing from the spirit of my invention, and in such modification the arm *f'* may be secured directly to the support without pivoting, the movement of the arm being effected through the natural resiliency of the metal of which both arm and catch are made. At the other end of the sign *e* is cut a socket *e*, preferably square in cross-section, in which socket a square key *g* is adapted to fit. This key *g* is formed on one end of a shaft *g'*, mounted to revolve in a

suitable bearing in the frame d , and to the other end of the shaft g' is secured a miter-gear g^2 . On the outside of the frame d , and inclosing the miter-gear g^2 and shaft g' , is secured a bracket h , forming a bearing for a shaft h' , arranged at right angles to the shaft g' and having at one end a miter-gear h^2 , meshing with the miter-gear g^2 . The other end of the shaft h' is provided with a hand-wheel h^3 , or similar operating device, by means of which the shaft h' may be revolved. The shaft h' is flattened, as at h^4 and h^5 , the flattened portion resting between two leaf-springs i , secured to and projecting from the bracket h . These springs i yield slightly to permit the turning of the shaft h' , but act as a stop or brake upon the shaft to hold it in one of two positions, which correspond to the two operative positions occupied by the sign e when turned through the key g , gears g^2 and h^2 , and shaft h' . The construction and arrangement of the springs i and flattened shaft h' are illustrated in detail at Fig. 6. Supported upon the bar b , directly above the frame d and sign e , is placed a hood or reflector k , of any suitable reflecting material, such as bright tin, pasteboard, or other light flexible material. This hood is inclosed at its ends and supported by the two rigid plates m , one of which is pivotally secured, as at m' , to said bar b , while the other is recessed, as at m^2 , to receive the bar b , to which it is locked by means of a removable spring-catch m^3 , as clearly illustrated in Fig. 2. Projecting through an opening in the rear of the hood k are one or more incandescent lamps n , the light of which is collected by the hood and thrown upon the exposed face of the sign e . These lamps may be reached by lifting the hood upon its pivotal support m' , the catch m^3 being released to permit of the movement of the other end of the hood away from the bar b . The hood is protected or partially inclosed by a bent rod o , arranged parallel with the rod b and extending around the dome of the hood. When the sign is used

upon a trolley-car, the rope p of the trolley will rest upon the two braces or rods b and o without touching the hood k , as illustrated in Fig. 4 of the drawings.

It is obvious that modifications may be made in the mechanical construction of certain of the elements of my invention without departing from the spirit of my invention. Thus, for instance, instead of flattening the shaft h' a flat-faced collar may be placed on the shaft between the springs i .

Having thus described the nature and objects of my invention, what I claim as new, and desire to secure by Letters Patent, is—

1. In a revoluble sign and reflector therefor, the combination of a frame, a sign-board revolving therein and removable therefrom, a key adapted to revolve the sign and supported in said frame, means for turning said key, and a reflecting-hood connected with said frame, substantially as and for the purposes described.

2. In a revoluble sign and reflector therefor, the combination with a reflecting-hood, of a frame supporting said hood, a sign-board revolving in said frame and removable therefrom, a key adapted to revolve said sign, means for actuating said key and means for braking the revolution of said key to thereby present the face of the sign in operative position, substantially as and for the purposes described.

3. In a revoluble sign, the combination of a frame, a sign-board revolved therein and removable therefrom, a key adapted to revolve said sign and supported in said frame, and means for actuating and braking said key, substantially as and for the purposes described.

In testimony whereof I have hereunto set my signature in the presence of two subscribing witnesses.

HENRY F. SCHWARTZ.
